DESIGN FOR A BATTERY PLATE ASSEMBLY

Benjamin D. Emanuel, Anderson, Ind.

Application October 5, 1938, Serial No. 80,283

Term of patent 14 years

To all whom it may concern:

Be it known that I, Benjamin D. Emanuel, a citizen of the United States of America, residing at Anderson, in the county of Madison and State of Indiana, have invented a new, original, and ornamental Design for Battery Plate Assembly, of which the following is a specification, reference being had to the accompanying drawing, forming part thereof.

In the drawing:—

Figure 1 is an upper edge view of a battery plate assembly, showing my new design;

Figure 2 is side elevational view of the same; and

Figure 3 is a sectional view on line 3—3 of Figure 2.

I claim:

The ornamental design for a battery plate assembly, as shown.

BENJAMIN D. EMANUEL.
